US0D1063616S

(12) **United States Design Patent** (10) Patent No.: **US D1,063,616 S**
(45) Date of Patent: ** Feb. 25, 2025

(54) **CAP FOR FLUIDS PACKAGE**

(71) Applicant: **SIG Combibloc (Suzhou) Co., Ltd.**,
Suzhou (CN)

(72) Inventors: **Remo Zürcher**, Jiangsu (CN);
Qiangyang Liang, Jiangsu (CN)

(73) Assignee: **SIG Combibloc (Suzhou) Co., Ltd.**,
Suzhou (CN)

(**) Term: **15 Years**

(21) Appl. No.: **35/519,792**

(22) Filed: **Jan. 20, 2023**

(80) **Hague Agreement Data**

Int. Filing Date: **Jan. 20, 2023**

Int. Reg. No.: **DM/227451**

Int. Reg. Date: **Jan. 20, 2023**

Int. Reg. Pub. Date: **Jan. 26, 2024**

(30) **Foreign Application Priority Data**

Jul. 26, 2022 (CN) 202230479540.8

(51) **LOC (15) Cl.** **09-07**

(52) **U.S. Cl.**

USPC **D9/453**

(57) **CLAIM**

The ornamental design for a cap for fluids package as shown and described.

DESCRIPTION

1. Cap for fluids package

1.1 : perspective view 1

1.2 : perspective view 2

1.3 : Front

1.4 : Right

1.5 : Top

1.6 : Bottom

1.7 : Left

1.8 : Back

The colors of the cap for fluids package form no part of the claimed design.

1 Claim, 8 Drawing Sheets
